CLAIM

The ornamental design for a display screen with graphical user interface, as shown and described.

DESCRIPTION

FIG. 1 is a front elevational view of a display screen with graphical user interface according to my design; and, FIG. 2 is an enlarged view of the area defined by 2-2 in FIG. 1.

The outermost broken lines illustrate a display screen and form no part of the claimed design. The dot-dash broken line illustrates the boundary of the enlarged drawing view defined by 2-2 in FIG. 1 and forms no part of the claimed design. The remaining broken lines, including the small circular portions and arcs, illustrate portions of the graphical user interface that form no part of the claimed design.

1 Claim, 2 Drawing Sheets
